UNITED STATES PATENT OFFICE.

OLIN S. FELLOWS, OF MIDDLETOWN, NEW YORK.

MEANS FOR REMOVING SUPERFLUOUS SOLDER FROM SHEET-METAL CANS.

SPECIFICATION forming part of Letters Patent No. 725,430, dated April 14, 1903.

Application filed October 18, 1902. Serial No. 127,758. (No model.)

To all whom it may concern:

Be it known that I, OLIN S. FELLOWS, a citizen of the United States, residing at Middletown, Orange county, and State of New York, have invented certain new and useful Improvements in Means for Removing Superfluous Solder from Sheet-Metal Cans, of which the following is a specification sufficient to enable others skilled in the art to which the invention appertains to make and use the same.

In solder-saving machines heretofore designed and constructed in which a brush is used for the removal of superfluous solder from the edges of the can the latter has always been sustained against the action of the brush by rigid unyielding rails or supports.

An important feature of my present invention consists in substituting for this rigid unyielding support an elastic resilient support, which tends constantly to press the cans against the brush, and thereby compensate for any slight inequalities in size or shape that may exist between the cans. It also adapts the apparatus to the treatment of elliptical and other shapes of cans approximating more or less the cylindrical form of can, since both the brush and the opposed can-supporting surface will conform within certain limits to variations in the diameter of a can under treatment.

My invention also relates to a peculiar form of opening in the nozzle by which the steam or other fluid blast is directed against the end plate of the can after the cylindrical end thereof has been subjected to the action of the brush and to the method of arranging and supporting the operative parts. My invention also includes a special combination and arrangement of parts, whereby the clogging of the cans in the machine is avoided, their discharge being insured by positive means, as hereinafter set forth.

It also includes certain other special features of construction hereinafter described and claimed specifically.

In the accompanying drawings, Figure 1 is a front elevation of my improved apparatus; Fig. 2, a horizontal section taken upon plane of line 2-2, Fig. 1; Fig. 3, a rear elevation of the apparatus; Fig. 4, an end elevation; Fig. 5, a vertical section; Figs. 6, 7, and 8, detail views of the fluid-blast.

A distinguishing feature of my present construction consists in arranging the power-pulleys and driving-belts on one side of a supporting wall or partition, with the can-forwarding and retarding and the solder-removing mechanism upon the other side of said partition; the bearings for the several shafts being all formed or mounted on this central support. By this means the driving mechanism is isolated from the solder-removing mechanism and from the dirt and dust unavoidably consequent upon the use of the latter. The driving mechanism is also rendered more accessible for cleaning and other purposes, as is also the solder-removing mechanism, since the transverse shafts thereof are supported entirely in this central partition, leaving the front of the apparatus free of bearings or similar obstructions.

In the drawings, A represents the base or table of the apparatus, and B a vertical upright or partition extending practically the whole length of the apparatus and continuous in structure, excepting for the openings formed or provided for the several bearings hereinafter described.

The only transverse shaft that has additional support to that afforded by the wall or partition B is the shaft C, to which the power is directly applied by means of the belt c. The rear end of this power-shaft C is supported in an adjustable bearing d, mounted in the rear standard D, projecting upward from the bed or table A. This bearing is preferably suspended upon an adjusting-screw d' and slides upon ways d² d², forming the sides of the vertical slot d³, as will be understood by reference to Fig. 3. The power-shaft C also rests in an adjustable bearing b, situated between the ways b' b', forming the sides of the slot b², formed in the partition B, the said bearing b being suspended upon the adjusting-screw b³.

On the front end of the power-shaft C is mounted the pulley c', over which passes the endless forwarding-belt E, which also passes around the pulley f on the front end of the counter-shaft F, which latter is mounted in the bearing f', suspended adjustably upon the screw f² and traveling in the slot f³, formed in the partition B.

Below the forwarding-belt E is situated the

retarding-belt G, traveling over and between the pulleys h and h', situated, respectively, upon the shafts H and H', running in the fixed bearings b⁴ and b⁵, formed on the partition B. 5 The pulleys c', f, h, and h' are of the same diameter; but the two latter are driven at a slower rate of speed than the two first named by means of a belt O passing over a pulley h² of larger diameter on the shaft H' and a pulley f⁴ of smaller diameter on the counter-shaft F, thus causing the upper surface of the retarding-belt G to travel in the opposite direction to the under surface of the forwarding-belt E at a relative speed that will retard 10 the advance of the cans while under the action of the rotatable brush K.

Supporting-rails I and guide-rails J conduct the cans from the soldering-machine in between the opposed surfaces of the forward- 20 ing and retarding belts E and G, the guide-rails J extending through and beyond the apparatus, but the supporting-rail I ending near the pulley h' and being supplemented or continued by the rail I', interposed between the pulley h and the discharging-wheel L and retarding-wheel M, beyond which the cans are supported upon the extension-rail I². It will thus be seen that the cans while subjected to the action of the brush are supported upon the substantially parallel surface of the retarding-belt, which, being more or less elastic, sustains the cans against the action of the brush with a yielding pressure, which adapts itself to and compensates for 30 any slight inequality of size or shape in the cans, while holding the latter in positive contact with the brush, a result not before attained, since the cans have heretofore been subjected to the action of the brush while resting against rigid rails parallel to the brush. The advantage of the present arrangement is that the cans receive more thorough treatment, since an approximately even pressure of the brush is maintained on the edges of all 40 the cans and the removal of superfluous solder is uniform.

Taken in conjunction with the elastic resilient nature of the bristles composing the brush K, it will be seen that the yielding can- 50 supporting surface G adapts the apparatus to the treatment of elliptical and other approximately cylindrical forms of cans, it being borne in mind that the forwarding-surface E is also of a yielding resilient nature when 55 constructed as shown in the drawings. In this connection it is obvious that the relative positions of the brush and the elastic retarding-surface are of special importance in attaining the best results, and for this reason I 60 herein make the brush adjustable vertically above the substantially parallel and horizontal retarding-surface, although this feature of an elastic or yielding retarding-surface opposed to the brush is not necessarily confined 65 to the arrangement herein shown, since it is obvious that the parts may be arranged to so treat the cans while in an upright position or

in any position or angle of inclination intermediate between the horizontal and perpendicular with like result, the essential feature 70 of my invention in this regard being the opposing of a yielding resilient retarding-surface to the action of the brush.

As shown in the drawings, the cylindrical brush K is secured to the horizontal shaft k, 75 which is mounted in bearings k' k', which are adapted to be adjusted vertically toward or from the upper horizontal surface g of the retarding-belt G by any suitable mechanical expedient. Thus the bearings k' k' may be secured to slides k³ k², resting between ways b⁶ b⁶ b⁷ b⁷, constituting the sides of the slots b⁸ b⁹, formed in the partition B, said slides k² k³ being suspended upon adjusting-screws k³ k³. By this or similar means the 85 brush may be adjusted with accuracy with relation to the yielding retarding-surface g to attain the degree of tension or pressure desired.

When the yielding can supporting and retarding surface G consists of a belt, as in the accompanying drawings, suitable provision also is made for adjusting the tension thereof with relation to the forwarding-surface E. I thus have two adjustments affecting the elastic pressure to be exerted upon the cans—i. e., the adjustment of the resilient can-supporting surface G with relation to the can-forwarding surface E and the adjustment of the brush with relation to the resilient can-supporting 100 surface G. Obviously the latter adjustment may be effected by various mechanical expedients, and I do not confine myself to any particular means in this respect, the device shown in the drawings consisting of a tightening-roller G', bearing against the inner and under side of the belt G, the journal g' of said tightening-roller resting in a bearing-box g², which is adjustable in the yoke g³ by means of the screw g⁴ bearing upon the upper side of the box g² and acting against the resistance of the spring g⁵, pressing against the under side of said box. By thus providing for the adjustment of the tension-yielding can supporting and retarding surface with relation to the 115 can-forwarding surface to regulate the pressure exerted against the cans by said opposed surfaces and for the subsequent adjustment of the brush with relation to the can supporting and retarding surface for the purpose of 120 regulating the pressure of the bristles of the brush upon the cans it is obvious that the best and most accurate results may be attained.

Since it is desirable to rotate the brush at 125 a relatively high degree of speed, power is applied directly to a small pinion k⁴ on the shaft k by a belt k⁵ or by other well-known means.

The ways J and I' conduct the cans from the brush K and retarding-surface g to the rotary discharging-wheel L and retarding-wheel M, the lower of which, M, is secured to the shaft m, mounted in the stationary bearing b¹⁰ on

the partition B, and the upper one of which is secured to the shaft l , mounted in the movable bearing l' , secured to the slide l'' , resting in the slot b'' , formed in the partition B 5 and suspended upon the adjusting-screw l'' , so that the discharging-wheel L may be adjusted vertically with relation to the retarding-wheel M.

Pulleys l^4 and m^3 are respectively mounted 10 upon the shafts l and m on the rear side of the partition B and are connected by a belt N, which also passes over the pulley h^3 on the rear end of the shaft H, from which power is transmitted to the wheels L and M in such 15 manner that they rotate in opposite directions, the diameter of the upper discharging-wheel L being a small fraction of an inch less than the diameter of the opposed lower wheel M, so that the can is finally discharged from 20 between them onto the exit-rails I^2 .

It will be seen that the end i' of the rail I' , adjoining the discharging-wheel L and retarding-wheel M, is made concentric to the center of said upper or discharging wheel L for a distance sufficient to insure the contact of a can 25 with said discharging-wheel L before the periphery of the retarding-wheel M is reached by the can. This is to insure the positive displacement of the cans by each other successively 30 from between the discharging-wheel L and retarder M, and thereby prevent the collecting or clogging of the cans within the apparatus. Thus even should the cans congregate on the rail I' so closely as to even be in actual contact with each other they cannot be held back 35 by the can between the wheels L M, since the next succeeding can will be grasped by the discharging-wheel L as soon as said can reaches the concentric portion i' of the rail I' and will 40 be thereby positively forwarded over said concentric portion i' , driving the preceding can off the retarding-wheel M, to be in turn displaced in like manner, and so on continuously. This feature of the concentric rail is 45 of special importance in connection with the support and treatment of the cans on their cylindrical sides with their longitudinal axes substantially horizontal, as herein shown, for the reason that the forwarding-belt E sends 50 the cans forward along the supporting-rail I' with an increased impetus as soon as the cans clear the retarding-belt G, and if they follow each other very closely they are apt to come 55 in contact, collect, and finally clog the machine—a difficulty which I have obviated by making the end of the rail I' with a portion i' concentric to the discharging-wheel L, as above set forth. I am aware that in my Patent No. 595,705, dated December 21, 1897, I 60 show a concentric rail opposed to a forwarding-wheel; but in that case the cans are treated on end vertically instead of horizontally, whereas in the present case I have expressly devised the concentric portion i' for use in 65 conjunction with the straight portion of the horizontal rail I' and with the horizontal forwarding and retarding belts E and G for the

purpose of counteracting the tendency of the cans to collect and clog on the rail I' by reason of the accelerated speed given the cans by 70 the forwarding-belt E after they clear the retarding-belt G, as before stated. The concentric portion i' of the rail must be sufficient in degree to represent an arc of a circle that will insure contact of the periphery of the discharging-wheel with at least two cans simultaneously, as shown in Fig. 1; otherwise a can rotating between the discharging and retarding wheels L M would hold succeeding cans back until such time as the discharging-wheel L dismissed the can under immediate treatment, whereas the design is to cut this supplemental treatment short by automatic means should the accumulation or rapid succession of cans from the brushing mechanism 85 render this expedient or necessary, the shortening of the supplementary treatment being less objectionable than the clogging and obstruction of the apparatus.

The supplemental treatment of the cans after brushing and preparatory to their discharge from the apparatus may be resorted to for various purposes, as for cooling the can by means of a jet of cold air or other fluid or for brushing or polishing the edge or end plate 90 by suitable means, and hence I do not confine myself to the use of the fluid-jet herein described, the essential feature of my invention in this respect being the combination, with the cylindrical brush and parallel means 95 for preserving and forwarding the cans in a practically straight line, of an auxiliary retarding-wheel and a discharging-wheel arranged to rotate a can temporarily between them while it is subjected to supplemental 100 treatment, together with a can-supporting rail interposed between the brushing mechanism and the said retarding and discharging wheels when said interposed can-supporting rail is formed with a portion concentric to the said 105 discharging-wheel of an extent sufficient to insure the possible contact simultaneously of at least two cans with the periphery of the discharging-wheel for the purpose of effecting the displacement of a preceding can by a 110 succeeding can by actual contact therewith should the cans follow each other at very short intervals or collect upon said can-supporting rail, as hereinbefore indicated.

In the arrangement shown in the accompanying drawings each can is held in turn by and between the retarder-wheel M and the discharging-wheel L, where it is subjected to a jet of steam, hot air, or other fluid directed to impinge against the edge of the end plate 115 for the purpose of removing the superfluous solder from said end plate, the brush having acted only on the flange of the end plate and the adjoining cylindrical portion of the can-body. In practice the action of the brush 120 tends to throw up or leave a slight bur or ridge of solder on or just beyond the apex or angle between the end plate and its flange. I have discovered that by making the discharge- 125

opening q in the steam or fluid nozzle Q either elongated or pear-shaped, substantially as indicated in Figs. 6, 7, and 8, and by thus opposing a narrow portion q' of the opening q to the extreme edge of the can I am enabled to attain a knife-like jet of steam or fluid that is much more effective in removing the bur or ridge of solder from the apex than any form of nozzle heretofore devised or used. In fact, as heretofore formed the jets of fluid under pressure directed against the inner side of the end plates have had a tendency to augment the bur or ridge deposited upon the apex by the action of the brush, a tendency which is fully overcome by my special construction of nozzle, which at the same time is effective in removing the accretion caused by the action of the brush.

A receptacle or flue R is arranged to receive the blast and solder deflected from the bottom s of the can S. This compartment R may be connected with air-exhaust mechanism T by means of a flue t , so that the air surrounding the retarding-wheel M, the discharging-wheel L, and the fluid-blast nozzle Q is drawn into the receptacle R, carrying with it the condensed steam or vapor, together with the detached solder, which by reason of its weight settles into the bottom of the compartment.

The exhaust mechanism T may be omitted, if desired, the blast being relied upon to draw into the top of the flue the air around the mouth thereof, in which case an aperture, as the flue t , may be left open near the lower end of the receptacle R or any tendency to back pressure otherwise obviated. Where steam under pressure is used for the blast, the condensation of the same within the receptacle will create a partial vacuum therein that will tend to draw in the air, &c., as above stated. For a like reason I design in some cases to inclose the brush in a casing T', abutting at the rear against the wall or partition B, said casing being provided with a door or cover t' to afford access to the brush and adjoining parts when necessary.

Air, dust, &c., are withdrawn from the interior of the casing T' by means of the exhaust flue U and fan V or equivalent mechanism.

What I claim as my invention, and desire to secure by Letters Patent, is—

1. In a solder-saving machine the combination of mechanism for removing superfluous solder from the ends of cans, driving mechanism for operating said solder-removing mechanism and a suitable base formed with an upright wall or partition interposed between said solder-removing mechanism and said driving mechanism, and provided with bearings for the support centrally, of the several transverse shafts of the apparatus, whereby the driving mechanism is isolated from the solder-removing mechanism while the ends of the said transverse shafts are rendered free and accessible, substantially as and for the purpose set forth.

2. In a solder-saving machine the combination of brush mechanism for removing superfluous solder from the ends of the cans, driving mechanism for operating said can-brushing mechanism, and a suitable base formed with an upright wall or partition interposed between said can-brushing mechanism and said driving mechanism and provided with bearings for the support, centrally, of the several transverse shafts of the apparatus, whereby the driving mechanism is isolated from the solder-removing mechanism while the ends of said transverse shafts are rendered free and accessible, substantially as and for the purpose described.

3. In a solder-saving machine, the combination of a horizontal brush for removing superfluous solder from the ends of cans, mechanism for conveying and presenting the cans to said horizontal brush and conveying them therefrom, a horizontal can-support opposed to said brush for sustaining the cans against the action of the brush, a casing inclosing the said horizontal brush and said opposed can-supporting surface and mechanism for adjusting said brush vertically with relation to said opposed horizontal can-support, substantially as described.

4. In a solder-saving machine, the combination of a brush for removing superfluous solder from the ends of cans, a yielding resilient can-sustaining surface adapted to engage the cylindrical bodies of the cans and support the cans with an elastic pressure against the action of the brush in the absence of a rigid support for the cylindrical bodies of the cans opposed to the brush whereby variations in the size or shape of the cans are compensated for, and mechanism for conveying the cans to and from said brush and said opposed resilient can-sustaining surface, substantially as set forth.

5. In a solder-saving machine, the combination of a brush for removing superfluous solder from the ends of cans, a yielding resilient can-sustaining surface adapted to engage the cylindrical bodies of the cans and to support the cans with an elastic pressure against the action of the brush in the absence of a rigid support for the cylindrical bodies of the cans opposed to the brush, whereby variations in the size or shape of the cans are compensated for, mechanism for conveying the cans to and from said brush and said opposed resilient can-sustaining surface, and means for adjusting the said brush with relation to the said opposed resilient can-sustaining surface, substantially as set forth.

6. In a solder-saving machine, the combination of a brush for removing superfluous solder from the ends of cans, mechanism for conveying and presenting cans to said brush and conveying them away therefrom, a yielding, resilient can-support opposed to said brush for sustaining the cans against the action of the brush with an elastic pressure, and means for adjusting the tension of said elastic can-

support for the purpose and substantially in the manner described.

7. In a solder-saving machine, the combination of a brush for removing superfluous solder from the ends of cans, a can-forwarding surface for conveying the cans past the brush, an elastic resilient can supporting and retarding surface opposed to the action of said brush and said can-forwarding surface, means for adjusting the tension of the said can-supporting surface with relation to the can-forwarding surface, and means for adjusting said brush with relation to the said resilient can supporting and retarding surface as and for the purpose set forth.

8. In a solder-saving machine, the combination of a brush for removing superfluous solder from the ends of cans, an elastic, resilient can-forwarding surface for conveying the cans past the brush, an elastic resilient can supporting and retarding surface opposed to the action of the said brush and the said elastic resilient can-forwarding surface and means for adjusting the tension of the said elastic resilient can supporting and retarding surface with relation to said elastic resilient can-forwarding surface and said brush, substantially as and for the purpose set forth.

9. In a solder-saving machine, the combination of a rotatable cylindrical brush for removing superfluous solder from the ends of cans, a yielding resilient can-sustaining surface adapted to engage the cylindrical bodies of the cans and support the cans with an elastic pressure against the action of the brush in the absence of a rigid support for the cylindrical bodies of the cans opposed to the brush, whereby variations in the size or shape of the cans are compensated for, and mechanism for conveying the cans to and from said brush and said opposed resilient can-sustaining surface, substantially as set forth.

10. In a solder-saving machine, the combination of a cylindrical brush for removing superfluous solder from the ends of cans, a can-forwarding surface consisting of an endless belt arranged to convey the cans past said cylindrical brush, and a yielding resilient can-sustaining surface adapted to engage the cylindrical bodies of the cans and support the cans with an elastic pressure against the action of the brush in the absence of a rigid support for the cylindrical bodies of the cans opposed to the brush, whereby variations in the size or shape of the cans are compensated for, said resilient can-sustaining surface consisting of an endless belt opposed to the said can-forwarding belt and traveling in the opposite direction, so as to retard the progress of the cans subjected to the action of said cylindrical brush, together with guide-rails for conveying the cans to and from the said brush and the resilient can supporting and retarding belt opposed thereto, substantially as set forth.

11. In a solder-saving machine, the combination of a cylindrical brush for removing su-

perfluous solder from the ends of cans, an elastic resilient can-forwarding surface consisting of an endless belt arranged to convey the cans past the said cylindrical brush, an elastic resilient can supporting and retarding surface consisting of an endless belt opposed, and rotating in the opposite direction to said can-forwarding belt and arranged to press the cans against the said cylindrical brush, and means for regulating the tension of said elastic resilient can supporting and retarding belt, substantially as set forth.

12. In a solder-saving machine, the combination of a cylindrical brush for removing superfluous solder from the ends of cans, a can-forwarding surface consisting of an endless belt arranged to convey the cans past said cylindrical brush, and a yielding resilient can-sustaining surface adapted to engage the cylindrical bodies of the cans and to support the cans with an elastic pressure against the action of the brush in the absence of a rigid support for the cylindrical bodies of the cans opposed to the brush, whereby variations in the size or shape of the cans are compensated for, said resilient can-sustaining surface consisting of an endless belt opposed to the said can-forwarding belt and traveling in the opposite direction, so as to retard the progress of the cans subjected to the action of said cylindrical brush, together with means for adjusting the said cylindrical brush with relation to the opposed resilient surface of said endless can-sustaining belt, substantially as set forth.

13. In a solder-saving machine, the combination of a cylindrical brush for removing superfluous solder from the ends of cans, an elastic resilient can-forwarding surface consisting of an endless belt arranged to convey the cans past the cylindrical brush, an elastic resilient can supporting and retarding surface consisting of an endless belt opposed, and rotating in the opposite direction to said can-forwarding belt and arranged to press the cans against the said cylindrical brush, means for regulating the tension of the said elastic resilient can supporting and retarding belt, and means for adjusting said cylindrical brush with relation to said opposed elastic resilient can supporting and retarding belt, substantially as set forth.

14. In a solder-saving machine, the combination of mechanism for brushing superfluous solder from the cylindrical edges of cans, said brushing mechanism consisting essentially of a cylindrical brush and parallel forwarding and retarding belts arranged to treat the cans while resting in a substantially straight line on their cylindrical sides with their axes extending horizontally, or nearly so, a retarding-wheel and a discharging-wheel arranged to rotate a can temporarily between them while it is subjected to supplemental treatment after brushing, and a can-supporting rail interposed between said brushing mechanism and said retarding and discharging

wheels, said interposed supporting-rail being formed with a portion concentric to the said discharging-wheel, whereby two cans may engage the periphery of said discharge-wheel 5 simultaneously for the purpose of effecting the displacement and discharge of a preceding can by a succeeding can, substantially as and for the purpose set forth.

15. In a solder-saving machine the combination of mechanism for brushing superfluous solder from the cylindrical edges of cans, consisting essentially of a brush, forwarding-belt, and retarding-belt arranged to treat the cans while resting on their cylindrical sides 15 with their axes arranged horizontally, or substantially so, mechanism for subjecting each can successively, after being so brushed to the action of a jet of steam or other fluid, consisting of a retarding and a discharging wheel and a nozzle arranged to blow such fluid-jet against the end plate of a can rotated between said retarding and discharging wheels, and a stationary can-supporting rail interposed between said brushing mechanism 20 and said fluid-blast mechanism, said intermediate rail being formed with a portion concentric to the said discharging-wheel, whereby succeeding cans may be made to positively displace the preceding can, substantially as 25 set forth.

16. In a solder-saving machine the combination of can-retarding mechanism and a nozzle for directing steam or other fluid against the edge of an end plate of a can rotated by 35 said retarding mechanism, said nozzle being formed with an elongated opening extending transversely across the annular path in which the extreme edge of the can travels while rotated by the said retarding mechanism substantially as and for the purpose set forth.

17. In a solder-saving machine the combination of can-retarding mechanism and a nozzle for directing steam or other fluid against the edge of an end plate of a can rotated by 45 said retarding mechanism, said nozzle being formed with an elongated opening which is contracted at a point opposite the position which the extreme edge of the can passes while rotated by the said retarding mechanism, for the purpose set forth.

18. In a solder-saving machine the combination of mechanism for brushing superfluous

solder from the cylindrical edges of cans, supplementary can-retarding mechanism for rotating the cans after they have been brushed, 55 and a nozzle for directing steam or other fluid against the edge of an end plate of a can rotated by said retarding mechanism, said nozzle being formed with an elongated opening extending transversely across the annular 60 path in which the extreme edge of the can travels while rotated by the said retarding mechanism, substantially as and for the purpose set forth.

19. In a solder-saving machine the combination of mechanism for brushing superfluous solder from the cylindrical edges of a can, supplementary can-retarding mechanism and a nozzle for directing steam or other fluid against the edges of an end plate of a can 70 held by said retarding mechanism, said nozzle being formed with an elongated opening which is contracted at a point opposite the position which the extreme edge of the can passes while rotated by the said retarding 75 mechanism, for the purpose set forth.

20. In a solder-saving machine the combination of can-retarding mechanism arranged to rotate a can in a substantially horizontal position axially, a nozzle arranged to direct 80 a blast of steam or other fluid downward against the inner edge of an end plate of a can rotated by said retarding mechanism, and a flue arranged with its mouth under and in proximity to said fluid-blast, whereby the 85 solder detached by the fluid-blast is precipitated into the said flue, substantially as set forth.

21. In a solder-saving machine the combination of can retarding mechanism arranged 90 to rotate a can in a substantially horizontal position axially, a nozzle arranged to direct a blast of steam or other fluid downward against the inner edge of an end plate of a can rotated by said retarding mechanism, a 95 flue arranged with its mouth under and in proximity to said fluid-blast, and mechanism for exhausting the air from said flue and thereby drawing into the flue the solder detached by the fluid-blast, substantially as set forth. 100
